UNITED STATES PATENT OFFICE.

THORE J. SESBY, OF KALISPELL, MONTANA.

ROLLER SKATE.

Application filed September 30, 1925. Serial No. 59,708.

This invention relates to improvements in skates and has particular reference to the roller type of skate.

An important object of the invention is 5 to provide a roller skate of the two wheel type designed to permit safe as well as convenient operation thereof.

A further object of the invention is the provision of a skate of the above character 10 wherein the frame structure will be suspended below the wheel centers so as to afford more efficient balancing ability.

A still further object of the invention is the provision of a roller skate of the above 15 type which may be quickly and comfortably attached to the foot of the user and thus facilitate the use of the skate.

Another object of the invention is the provision of a roller skate of comparatively 20 simple yet durable construction designed to permit comparatively safe use, and which may be manufactured at a comparatively low cost.

Other objects and advantages of this 25 invention will become apparent as the description progresses.

In the accompanying drawing forming a 30 part of this specification and in which like numerals are employed to designate corresponding parts throughout the same:

Figure 1 is a side elevation of a skate constructed in accordance with my invention, and

Figure 2 is a top plan view of the same.

In the drawing, wherein for the purpose 35 of illustration is shown the preferred embodiment of my invention, the numeral 5 generally indicates the foot supporting frame which is composed of a bottom plate 6 shaped so as to conform to the curvature 40 of the sole of a shoe and preferably constructed of durable metal or similar material. Secured upon the top side of the bottom plate 6 adjacent the edge thereof is a continuous side rail 7 disposed in a vertical 45 position and provided at the sides with ornamental recesses 8 tending to lighten the structure and improve the appearance thereof. The side rail 7 is also of metallic or 50 similar construction preferably in the form of sheet metal so as to withstand severe usage.

Positioned against the inner side of the 55 side rail 7 and secured to the rear portion thereof is an upwardly extending heel brace 9 of substantially semi-circular formation,

this brace being preferably constructed of leather or similar material. The upper edge of the heel brace 9 is provided with a pair of forwardly projecting extensions 10 arranged in opposed relation, one of these extensions carrying a conventional type of strap buckle 11 while a comparatively narrow strap 12 is riveted or otherwise secured to the opposite extension. This heel brace 15 is secured to the rear portion of the side rail by rivets 13 or in any suitable manner so as to securely retain the brace in a rigid vertical position. This construction will permit the foot of the user to be readily 20 positioned upon the foot frame and the heel portion snugly fitted against the heel brace 9, the strap 12 being in an open position while the foot is being placed therein. After the foot has been placed comfortably 25 on the brace the strap 12 is fastened in the buckle 11 and the ankle snugly held in position.

In order that the forward portion of the shoe may be securely fastened upon the foot 30 frame I provide a transversely adjustable clamp 14 of common structure, this clamp embodying a pair of angular clamp plates movably held in position by suitable brackets 15. The clamp plates are provided 35 with downward projections provided with threaded openings engageable with a screw 16 having right and left hand threads, so that rotation of the screw will actuate the clamp plates to adjacent or remote positions 40 so as to readily engage the sole of a shoe.

The forward and rear extremities of the foot frame carry a pair of wheel brackets 45 17 comprised of a pair of tapered bracket bars 18 extending forwardly and rearwardly in angular positions. These bracket plates are formed integral with or connected to a pair of spaced wheel supporting sleeves 19 of circular formation. As is evident 50 from the drawing, these sleeves are disposed in elevated positions relative to the foot frame of the skate and are adapted to rotatably support rollers or wheels 20.

These rollers, in the present instance, embody rims 21 arranged concentrically about 55 comparatively small hubs these members being connected by wire spokes 22 or in any suitable manner. The rims 21 are formed in an arcuate manner so as to readily carry tires 23 of rubber or like structure.

The wheels, of which there are two in 60 number in the present embodiment shown,

are mounted in association with the skate frame by positioning the wheel frame between the sleeves 19 and placing in position a transversely mounted axle. In order 5 to facilitate the movement of the wheels about the axle I contemplate the positioning of ball bearings between the outer edges of the sleeves 19 and the axles, these bearings being covered by suitable dust caps 24 and 10 retained in position by nuts 25 threadedly mounted on the axles.

It is obvious from the foregoing description and the drawing, that a compact and durable skate of comparatively simple design 15 sign is provided, the relative positions of the wheels to the foot frame being arranged so that the frame is in a central underslung position, the center of gravity of the frame being naturally lower than the wheel axles. 20 This construction will render the use of skates of this type comparatively safe and will relieve the ankles of the user of the strain occasioned by skates where the frame is in an elevated position. With this in 25 mind, it will be readily seen that a highly practical skate of the two wheel variety is produced.

It is to be understood that the form of my invention herewith shown and described 30 is susceptible of modification and that various changes as to the shape, size and arrange-

ment of parts may be resorted to without departing from the spirit of the invention or the scope of the subjoined claims.

Having thus described my invention, I claim:

1. In a roller skate, a bottom plate shaped to conform to the sole of a shoe, wheels carried by the front and rear ends of said plate, a continuous side rail disposed in a vertical 40 position and carried by the bottom plate and provided with recesses, a heel brace carried by said side rail, and transversely adjustable clamps carried by the bottom plate and extending inwardly through the 45 recesses to engage the sole of the shoe.

2. In a roller skate, the combination with a bottom plate shaped to conform to the sole of a shoe, and wheels carried by the said plate, of a continuous side rail disposed 50 in a vertical position and carried by said plate, said side rail being also shaped to conform to the sole of a shoe and provided with recesses, a heel brace carried by said rail, and transversely adjustable clamps supported by the plate and extending inwardly 55 through the recesses in the rail to engage the sole of the shoe.

In testimony whereof I affix my signature.

THORE J. SESBY.
